CLAIM

The ornamental design for an assembling toy, as shown and described.

DESCRIPTION

FIG. 1 is a front view of an assembling toy of the present invention in a closed position.

FIG. 2 is a rear elevational view thereof.

FIG. 3 is a top plan view thereof.

FIG. 4 is a bottom plan view thereof.

FIG. 5 is a right-side elevational view thereof.

FIG. 6 is a left-side elevational view thereof.

FIG. 7 is a top perspective view thereof.

FIG. 8 is a top perspective view thereof in a moved position.

FIG. 9 is a bottom perspective view of FIG. 1.

FIG. 10 is a bottom perspective view of FIG. 8.

FIG. 11 is a sectional view thereof taken along section line 11-11 of FIG. 3; and,

FIG. 12 is an enlarged view of the portion indicated by arrows 12-12 of the assembling toy of FIG. 11.

The alternating long and short dashed lines indicate bounds of the claimed design and form no part thereof.

The broken lines are for the purpose of illustrating portions of the article that form no part of the claim.

1 Claim, 12 Drawing Sheets
